UNITED STATES PATENT OFFICE.

CARL G. DANIELSON, OF KANSAS CITY, MISSOURI.

METALLIC DOOR.

1,082,071.

Specification of Letters Patent. Patented Dec. 23, 1913.

Application filed December 21, 1911. Serial No. 667,075.

To all whom it may concern:

Be it known that I, CARL G. DANIELSON, a citizen of the United States, residing at Kansas City, in the county of Jackson and 5 State of Missouri, have invented certain new and useful Improvements in Metallic Doors, of which the following is a specification.

My invention relates to improvements in 10 metallic-doors, and the like, and one object of the invention is to provide a novel molding whereby the panels may be firmly secured to the stiles and rails of a door without welding or employing rivets; thus materially reducing the cost of construction 15 without sacrificing strength or other desirable features of a door of this character.

My improved molding is made separate 20 from the stiles and rails, and embodies grooves for the margins of the panels and locking members adapted to be readily slid into engagement with corresponding locking members on the stiles and rails, to reliably secure the panels thereto.

Other objects of the invention will hereinafter appear and in order that said invention may be fully understood, reference 25 will now be made to the accompanying drawing, in which:

Figure 1 is an elevation partly in section of my improved door. Fig. 2 is an enlarged section on line II-II of Fig. 1, and Fig. 3 is a section of a modified form of the invention.

1 designates the hollow stiles, 2 the hollow rails, and 3 the panels of the improved door. Panels 3 are reliably secured to stiles 1 and rails 2 by molding 4, forming an important 35 feature of the invention. Molding 4 is cut into sections of proper length, which sections have mitered meeting ends 5, as shown in Fig. 1. Each section comprises one piece of sheet metal having a central longitudinal groove 6, to receive the adjacent margin of

45 a panel 3, as shown in Fig. 2. Groove 6 is formed by a central transverse wall 7 and two parallel walls 8, which latter are bent at right-angles to the former and spaced apart to admit the panel 3. The parallel 50 walls 8 are bent at right-angles in opposite directions to each other to form walls 9, bent to form walls 10, which are parallel with walls 8 and bent to form curved walls 11, communicating with walls 12, bent inward 55 toward each other to form a pair of locking-members 13, which terminate adja-

cent wall 7. Locking-members 13 are adapted to slide longitudinally into sockets formed by locking-members arranged in pairs on the stiles 1 and rails 2. Said pairs of locking-members are alike, and each pair is preferably formed integral with the inner side of its respective stile or rail. The inner ends of said locking members are in juxtaposition to walls 8 to prevent lateral movement 65 thereof.

Referring to Fig. 2, it will be seen that each pair of locking-members comprises two oppositely-disposed flanges 14 and two flanges 15, communicating at their inner 70 ends and spaced apart to form sockets 16, adapted to receive the locking-members 13 on the molding. Flanges 15 extend at right-angles to the side walls 17 of rail 2, which is stiffened by a transverse reinforcing member 18, bearing against flanges 15 and wall 7 to stiffen the same. The opposite edge of the rail is closed by a metallic-plate 19, the ends 20 of which are bent at right angles thereto and have longitudinal beads 21, to 80 engage corresponding resilient clamping-members 22 on a transverse reinforcing plate 23 paralleling plate 18 and secured to walls 17.

The rear edge of the door is reinforced by 85 a metallic bar 24, having recesses 25 to receive the hinges (not shown) whereby the door is hung.

In the form shown on Fig. 3, the molding is substantially the same shape as that 90 shown on Fig. 2, except that it is made in two pieces, one of which is held in place by screws 26, so that it can be readily removed should the glass panel 3a become broken. A cushion 27 is provided to permit the metal 95 portions of the door to expand and contract without fracturing the glass panel.

When the rails, stiles, and panels are connected as above described, a very rigid and durable door is obtained.

Window sashes and other like articles can be constructed according to this invention, as the drawing forming part of this specification is only intended to illustrate the invention in a representative way in connection with a metallic-door.

Having thus described my invention what I claim and desire to secure by Letters Patent, is:

A metallic door, or the like, consisting of 110 panels, hollow stiles and hollow rails, each stile and rail consisting of a pair of side

walls suitably connected at their outer edges and having inturned locking members at their inner edges, molding sections, each comprising one piece of sheet metal having 5 inturned locking members to interlock with the like elements on the rails and stiles and a groove to receive the adjacent edge of a panel, the adjacent sides of the first-mentioned locking members being in juxtaposition to the sides of said groove and arranged 10 in transverse alinement with the inner wall

thereof, and a reinforcing member connecting the walls of each stile and rail and abutting against the locking members thereof and the inner wall of a groove, substantially as shown and described. 15

In testimony whereof I affix my signature, in the presence of two witnesses.

CARL G. DANIELSON.

Witnesses:

F. G. FISCHER,
E. C. LILLIAN.
